[57] CLAIM

The ornamental design for a coffee dispenser, as shown and described.

DESCRIPTION

FIG. 1 is a top, front, left side perspective view of a coffee dispenser showing our new design;

FIG. 2 is a front elevation thereof;

FIG. 3 is a left side elevation thereof;

FIG. 4 is a right side elevation thereof;

FIG. 5 is a rear elevation thereof;

FIG. 6 is a top plan view thereof;

FIG. 7 is a bottom plan view thereof;

FIG. 8 is a perspective view of a second embodiment of that shown in FIG. 1.
